UNITED STATES PATENT OFFICE.

JUDSON P. HABENICHT, OF BERRIEN SPRINGS, MICHIGAN; FEDERICA E. HABENICHT EXECUTRIX OF SAID JUDSON P. HABENICHT, DECEASED.

CUFF BUTTON.

Application filed January 31, 1925. Serial No. 6,110.

This invention relates to improvements in cuff buttons and contemplates the provision of usual and ordinary types of cuff buttons which when used in combination with the holding means attached therewith will prevent loss as well as keeping the cuffs of the shirt in a fitting position with respect to the wrists of the wearer.

Another object of the invention is the provision of holding means which extend from the lower side of the cuff button or cuff links and which extend under the meeting ends of the cuff and attached to both of the lower sides of the cuff buttons or links in order that the said meeting ends of the cuff will be held in proper position and will not flare outwardly.

A further object of the invention is the provision of ring members adapted to be positioned on the shaft of the cuff buttons or upon the chains or connecting links of the cuff links and which are adapted to normally lie flush with the inner sides of the links or cuff buttons and having their lower end portions connected by a chain or other resilient or pliable member in the form of a chain which extends around and against the lower meeting ends of a cuff in order to prevent loss of the cuff links or cuff buttons as well as to keep the said meeting ends of the cuff in proper position as well as to form an attractive attachment to the cuff buttons, cuff links and to the general appearance of the cuff per se.

With the above and other objects in view, the invention further includes the following novel features and details of construction, to be hereinafter more fully described, illustrated in the accompanying drawings and pointed out in the appended claims.

In the drawing:

Figure 1 is a side elevation of a cuff showing a cuff button and the attachment applied thereto.

Figure 2 is a detailed perspective of a cuff link with the holding means applied or attached therewith.

Figure 3 is a similar view of a modified form of the invention with the holding means attached thereon.

Figure 4 is a perspective of a cuff link applied to a cuff and showing ring means applied therewith.

Figure 5 is a detailed perspective of the

cuff link with the ring means attached therewith.

Figure 6 is a similar view to Figure 4 and showing a link or chain member inserted in the button holes of the cuff and functioning in the capacity of the combined cuff link, cuff button and holding means.

Figure 7 is a plan view of the link or chain member.

Figure 8 is a perspective of a modified form of my invention shown as applied to a cuff.

Figure 9 is a transverse section taken through the modification.

Figure 10 is a side elevation of the invention showing the locking means.

Figure 11 is a longitudinal section of another modification.

Figure 12 is a sectional view of this modification showing the locking means therein.

Figure 13 is a similar view with a different form of link.

Referring to the drawing in detail, where in like characters of reference denote corresponding parts, the reference character 10 indicates a cuff of a shirt, not shown, and to which the present invention in the form of a preferred, and three modifications are adapted to be applied thereto.

Referring in detail to Figures 1 and 2 inclusive wherein the preferred form of my invention is shown and in which a pair of cuff links 11 are employed and include arcuate shaped loop members 12 which extend inwardly from the inner sides thereof and are connected through the instrumentality of a plurality of chain links 13 in order that the arcuate shaped loop members 12 may be connected and in so doing will connect the links 11 in order that the links per se may be completed, and in order to facilitate the supporting or connecting of the holding means before mentioned, there is provided openings 14 in the lower side thereof, one of which is adapted to receive a link of a chain 15 and the other opening 16 adapted to selectively receive a hook 16 after the cuff links have been positioned in the button holes of the cuff 10 and extended under the meeting ends of the cuff and connected or positioned within the opening 14 in the other link 11.

It will thus be seen that owing to the holding means in the form of a chain 15

which is connected to the lower sides of the links 11 that the cuff 10 will form a substantially wedge shape and snugly fit the wrist of the wearer and prevent the meeting ends of the cuff 10 from flaring outwardly in order to form a neat appearance of same.

In Figure 3 of the drawing, there is shown a modification of my invention which includes links 12 or arcuate shaped loop members 12 and a linked chain 13, this form of the invention includes a pair of loop members 17 extending from the lower side edges thereof, one of which is adapted to receive the end link of a chain 18 which has or includes upon the opposite end thereof a detachable hook member 19 which is adapted to selectively engage the opposite loop member 17 in order that the same may function within the same category as the form of the invention shown in Figures 1 and 2.

In Figures 4 and 5 of the drawings, wherein a second modification of my invention is clearly illustrated, I provide a usual and ordinary type of cuff button which includes an elongated relatively flat plate 20, an arcuate shaped bar 21 extending from the inner side thereof and including upon the opposite end portion thereof an oval shaped disk 22, which completes the usual and ordinary type of cuff button as aforementioned; in this form of the invention I provide a pair of oval shaped ring members 23 which are connected by a chain 24 and which link members are adapted to be positioned over the oval shaped disk members 22 and upon the arcuate shaped shaft or bar 21 and after the cuff button has been inserted within the button holes provided in the cuff 10 the other ring 23 is slipped over the oval shaped disk member 22 in order that the same may function within the same category as the preferred form and first modification respectively.

In Figures 6 and 7 of the drawings, wherein the third modification of my invention is shown, I have provided a chain 25 which includes a detachable hook member 26 which is adapted to receive the opposite end link of the chain 25 therein and the same is inserted within the button holes of the cuff 10 in order that the same may function in the same category as the combined cuff links, cuff buttons, and holding means therefor, as well as provide a very attractive and neat arrangement of cuff holding means.

In Figures 8, 9 and 10 on sheet 2 of the drawings, it is noted that a modification of the invention is shown as including a pair of link members 27 and 28, the link 27 including an arcuate shaped bar 29 which includes a cross bar 30 upon the opposite end portion thereof. The other link, namely, the link 28 includes a transversely disposed elongated slot 31 which is adapted to receive the cross bar 30 of the arcuate shaped bar 29

therethrough and when the arcuate shaped bar 29 and link 27 are turned a quarter turn it will be noted that the cross bar 30 and the arcuate shaped bar 29 will extend transversely of the elongated slot 31 whereby the links will be held against accidental displacement. In order to prevent loss of the links 27 and 28 there is provided a connecting chain 32 which has its opposite end portions connected to the lower ends or sides of the links 27 and 28 respectively.

Referring to Figures 11, 12 and 13 respectively on sheet 2 of the drawings and wherein another modification of my invention is shown and which include backs 33 which are preferably brass or the like and which include upon the upper sides thereof annular flanges 34 which extend upwardly therefrom an appreciable distance; these annular flanges 34 on the opposite links forming the complete cuff buttons are adapted to space 35 which is preferably formed of precious metal, such as gold and which has the edges thereof bent over the backs 33 as at 36. One of these links includes an arcuate shaped bar 37 which includes a transversely extending bar member 38 upon the outer free end portions thereof while the opposite companion link member includes an elongated opening 39 in the back 33, and which further includes within the space defined between the backs 33 and fronts 35, a spring 40 which is relatively flat and has its outer sides bearing against the inner walls of the annular flanges 34 and includes offset portions 41 and 42 which bring the meeting end portions of the spring 40 into superimposed relation and transversely of the elongated openings 39 provided therein.

It will thus be seen from the foregoing description and accompanying drawings that in this form, namely, as clearly illustrated in Figures 11, 12 and 13, that the bar member 38 upon the free end portion of the arcuate shaped bar 37 may be inserted at an angle within the elongated slots 39 and push the meeting end portions of the spring 40 downwardly in order to insert the remainder of the cross bar 38, the links carrying the arcuate shaped bar 37 and cross bars 38 are then rotated a quarter turn within the opposite links and the meeting end portions of the springs 40 are then brought against the side of the cross bars 38 in order to hold the same transversely of the elongated slots 39 provided therein.

In this form of the invention further loss of the cuff links is prevented by connecting the opposite end portions of the link 43 to the lower sides of the companion link member.

The invention is susceptible of various changes in its form, proportions and minor details of construction, and the right is herein reserved to make such changes as

properly fall within the scope of the appended claims.

Having thus described my invention what is claimed is:—

- 5 1. A cuff holding member of the character described comprising a pair of oval shaped members having openings provided adjacent one side edge thereof, loop members provided upon the inner sides thereof, linking means connecting said loop members, and connecting means positioned within the openings provided in the side edges of the links substantially as set forth.
- 10 2. A cuff holding member of the character described comprising a pair of substantially elongated plate members, loop members extending from the side edges and inner side portions thereof, linking means associating the loop means provided upon the inner sides of the plates and a chain member having one end link connected to one of the loop members provided upon the side edges and having a detachable hook member provided upon the opposite end portion thereof and adapted for selective engagement with the corresponding loop member provided upon the opposite plate member.
- 15 3. A cuff holder of the character described comprising a linked member having a detachable hook member provided upon one end thereof, said linked member adapted to be received within the button holes of a cuff and having its detachable hook member hooked to the opposite end of the link member whereby the lower meeting end portions of the cuff will be prevented from flaring outwardly.
- 20 4. A cuff holder of the character described comprising a pair of cuff links, one

of the links including an arcuate shaped bar member extending from the inner side thereof and which includes thereon a transversely disposed short bar upon the free end portions thereof, the opposite link member includes an elongated slot therein which receives the transversely disposed short bar therein, and an auxiliary chain member having its opposite ends connected to the sides of the link members.

5. A cuff holder of the character described comprising a pair of cuff links, the backs of the links including forwardly extending annular flanges thereon, a front for the links extending over the annular flanges of the backs and having their edges bent over the backs of the links, one of the links including an arcuate shaped bar having a relatively short transversely disposed bar provided upon the free end portion thereof, the opposite link member including a substantially elongated slot in the back and a relatively flat spring arranged with the space defined between the back and front of the links and bearing against the inner sides of the annular flanges, whereby the cross bars may be readily and easily inserted therein and having their opposite end portions extending centrally and transversely of the elongated slots provided in the backs whereby the relatively short transversely disposed bars may be readily and easily inserted within the elongated slots provided in the backs and held against accidental displacement therein through the spring tension of the meeting end portions of the spring.

In testimony whereof I affix my signature.

JUDSON P. HABENICHT.
